UNITED STATES PATENT OFFICE

THEODORE E. MUELLER, OF LOUISVILLE, KENTUCKY, ASSIGNOR TO STANDARD SANITARY MANUFACTURING COMPANY, OF PITTSBURGH, PENNSYLVANIA, A CORPORATION OF NEW JERSEY

DESIGN FOR A PEDESTAL

Application filed October 23, 1931. Serial No. 41,500. Term of patent 14 years.

To all whom it may concern:

Be it known that I, THEODORE E. MUELLER, a citizen of the United States, and residing at Louisville, in the county of Jefferson and State of Kentucky, U. S. A., have invented a new, original, and ornamental Design for a Pedestal, of which the following is a specification, reference being had to the accompanying drawings, forming a part thereof, wherein:

I claim:

The ornamental design for a pedestal, substantially as shown.

THEODORE E. MUELLER.
